UNITED STATES PATENT OFFICE.

FREDERICK L. MILLER, OF SOUTH BEND, INDIANA, ASSIGNOR TO THE STUDEBAKER CORPORATION, OF SOUTH BEND, INDIANA, A CORPORATION OF NEW JERSEY.

BODY HARDWARE.

Application filed May 2, 1927. Serial No. 188,253.

This invention relates to ornamental fixtures and particularly to an improved construction thereof, a corner lamp for enclosed vehicle bodies to which the present invention is applicable, being illustrated in the drawings and described in the following specification as a typical example of such fixture.

Heretofore changes in the design of an ornamental fixture such as a corner lamp have always been made by altering a portion of the same, each alteration and design irrespective of its magnitude necessitating the construction of a new die. Constructing a new die every time a small change in design is made is very costly, and it is, therefore, the principal object of this invention to provide an ornamental fixture which only necessitates the insertion of an ornamental portion to change the design of the exposed surfaces thereof, and does not necessitate the changing of the exposed surface proper.

Another object is to provide an ornamental fixture having an exposed surface provided with an aperture, and having an ornamental insert adapted to be positioned underneath the exposed surface whereby a portion of the insert is visible through the aperture in the exposed surface.

Another object is to provide an ornamental lamp fixture with an exposed apertured rim surrounding the transparent portion thereof, an ornamental insert being provided underneath the rim, portions of which are visible through the apertures in the rim.

Another object is to provide an ornamental lamp fixture with an exposed rim having apertures formed therein and a continuous insert positioned below the rim, embossed designs on the insert extending into the apertures in the rim.

These being among the objects of the present invention, the same consists of certain features of construction and combinations of parts to be hereinafter described with reference to the accompanying drawings, and then claimed, having the above and other objects in view.

In the accompanying drawings which illustrate a suitable embodiment of the present invention,

Figure 1 is a plan view of a lamp taken as an example of an ornamental fixture.

Figure 2 is a side elevation of the lamp shown in Figure 1.

Figure 3 is an enlarged transverse section of the lamp taken on the line 3—3 of Figure 1 showing the means for holding the ornamental insert in position.

Figure 4 is a plan view of the ornamental insert.

Figure 5 is a plan view of the back plate showing the positions of the insert retainer members thereon.

Figure 6 is a perspective view of one of the spring like retainer members.

Figure 7 is a plan view of the lamp base.

Figure 8 is an enlarged sectional view taken on the line 8—8 of Figure 1 showing the method of uniting the lamp base and cover assembly.

Figure 9 is a plan view of a window regulator handle illustrating another use of an ornamental insert.

Referring to the accompanying drawings 75 in which like numerals refer to like parts throughout the several views, the corner lamp construction which is taken as a typical example of an ornamental fixture, comprises two unitary assemblies, namely, a lamp base 80 and a cover which are secured together to form the complete lamp structure.

The lamp base as shown in Figures 2 and 3 consists of a deep rectangular-shaped housing 20 open at one side and containing a lamp socket 22 extended through and secured to an end wall thereof, a suitable lamp bulb 24 being retained in position by the socket 22. A pair of upstanding oppositely extending ears 23 are struck parallel to the flanges 21 from the metal of the same at opposite sides of the housing 20, as shown in Figures 7 and 8, to provide an attaching means, the purpose of which will be described later in the specification.

The lamp cover comprises a retaining rim 25 for the glass cover and a back plate 32. The retaining rim 25 is formed with a central opening 26 to receive a transparent glass 27, the edges of which are flanged at 28 and seat against the edge of the rim 25 forming the opening 26. Narrow apertures 29 are formed in the space between the inner and outer edges of the retainer rim 25, and surrounding the flanged portion 28 of the glass 27 and abutting against the under side of the rim 25 is the flat annular ring or insert 30, the plan view of which is shown in Figure 4. Embossed designs 35 are formed on the insert 30 and project into 110

the apertures 29 where they are visible from the exterior of the rim 25. The insert 30 is the principal feature of the present invention and it is this portion which is used to change the design of the fixture, it being necessary only to change the design on the insert to provide a fixture of different design.

Secured to the back plate 32, as shown in Figures 5 and 6, are a number of supports 31, the free ends of which are extended outwardly to provide spring fingers 36, which supports 31 when the back plate 32 is assembled to the rim 25, hold the flange edges 28 of the glass 27 in position in the retaining rim 25. The spring fingers 36 extending from the supports 31 bear against the insert 30 to hold the same firmly against the under side of the rim 25, the extreme ends of the fingers being flanged upwardly to prevent displacement of the insert 30, as shown in Figure 3.

The central portion of the plate 32 is cut away at 33 and at each side of this opening is a key hole slot 34. The back plate 32 is substantially smaller than the rim 25 so that when the two are assembled the edges thereof may be welded or soldered to provide a flat surface, that is, so that the plane of the bottom face of the back plate 32 will coincide with the plane of the lower edge of the rim 25 to provide flush surfaces therebetween.

The cover and lamp base assemblies are united by laying the cover on the base so that the upwardly extending ears 23 on the base flanges 21 are received by the enlarged portions of the key hole slots 34, and then, by sliding the cover along the surface of the flanges 21 so that the ears 23 engage with the narrow portions of the key hole slots 34 to securely unite the two assemblies, as shown in Figure 8. When in this assembled position, the rays of light from the lamp bulb 24 pass through the opening 33 in the plate 32 and out through the transparent glass 27.

The ornamental insert 30, shown in Figure 4, may be formed of leather, imitation leather, metal, or any other material capable of having a design, such as 35, formed thereon. Leather is a very desirable material to use for the insert as it may be easily embossed or tooled and may be painted with any color which, in case the fixture is used in a vehicle body, may match the body upholstery to give a pleasing appearance to the interior of the body.

Inserts of this description may be incorporated in a great many types or ornamental fixtures, Figure 9 illustrating the use of an embossed insert 40 incorporated in a window regulator handle 41, the insert 40 being positioned between the retaining rim 42 and the main body portion of the handle.

Any number of designs of ornamental fixtures may be had without changing the designs of the outer surfaces thereof, as it is only necessary to assemble inserts thereto having different designs. It is not necessary then to provide outer surfaces of many designs or shapes with the result that a great saving is effected in the construction of complicated dies.

It is to be understood that the present invention is not limited to the use of inserts of this description with any particular fixture, and that formal changes may be made in the specific embodiments of the invention described without departing from the spirit and substance of the broad invention, the scope of which is commensurate with the appended claims.

What I claim is:

1. An ornamental lamp fixture, comprising a housing having an outwardly extending flange, a backing plate secured to said flange, a glass cover having an outwardly extending flange spaced from said backing plate, supports on said backing plate to support said glass cover at the free edge thereof, an ornamental insert resting on said supports, and a retaining rim having apertures therein overlying said insert and the flange on said glass cover to secure said glass cover and insert to said housing.

2. An ornamental lamp fixture, comprising a housing, a cover therefor spaced therefrom, supports for said cover interposed between said cover and housing, said supports extending outwardly beyond said cover, an ornamental insert supported by the free ends of said supports, and a retaining rim having apertures therein overlying said insert and a portion of said cover for securing said cover and insert to said housing.

3. An ornamental lamp fixture, comprising a housing, an apertured plate secured thereto, supports secured to said plate, a glass cover seating on said supports, an ornamental insert exterior of said cover seated on said supports, and a retaining rim having apertures therein for overlying said insert and a portion of said cover to secure said cover and insert to said supports.

Signed by me at South Bend, Indiana, this 29th day of April, 1927.

FREDERICK L. MILLER.
